UNITED STATES PATENT OFFICE.

EMMELINE W. PHILBROOK, OF BOSTON, MASSACHUSETTS.

VENTILATING-SCREEN FOR WINDOWS.

SPECIFICATION forming part of Letters Patent No. 286,555, dated October 9, 1882.

Application filed March 26, 1883. (No model.)

To all whom it may concern:

Be it known that I, EMMELINE W. PHILBROOK, of Boston, in the county of Suffolk and State of Massachusetts, have invented a new and useful Improvement in Ventilating-Screens for Windows, which improvement is fully set forth in the following specification.

This invention has reference to ventilating-screens for use in the windows of dwellings or other buildings, or of railway-cars, the device being of the class that is adapted to be placed in the window-frame by opening the sash a sufficient distance to admit it, and held in place by closing the sash against it.

Window-ventilators have commonly been made with a frame covered with a netting of wire or other material, and provided with a cover or shield hinged at the bottom and adapted to be opened a greater or less distance, according as more or less air is required. In the present invention a shield or cover hinged to the frame is also employed, and in connection with it are provided devices which act automatically to hold the shield or cover at any desired angle. These devices consist of curved arms provided with a series of notches or indentations, which engage pins or projections on the ends of the shield. The arms are pressed against said pins with sufficient force to hold the shield in any position in which it may be placed. On the opposite side of the frame from the hinged cover or shield is an extension piece or slide moving in grooves in the back of said frame. The object of this slide is to afford greater nicety of adjustment to the air-opening, and also to enable the ventilator to fit windows of different widths. Along the lower edge of the frame is placed a metal strip let into the wood, and which forms a ledge or trough for catching any particles of dust that may sift through the screen.

The invention consists in the ventilator as a whole, in the several new improvements herein described, and in the particular constructions, combinations, and arrangements of parts, as hereinafter more fully set forth.

In the accompanying drawings, Figure 1 is a perspective view of a window-ventilator constructed in accordance with the invention; Fig. 2, a vertical section of the same, partly in elevation; Fig. 3, a front elevation of a portion of a screen, showing a two-part extension-piece;

Fig. 4, a rear elevation of the same, and Fig. 5 a detail view.

A is the frame, preferably of wood, inclosing a screen, *a*, of fine wire-netting or other perforate medium, the frame being made sufficiently strong to support the weight of the window-sash.

To the bottom strip of the frame is hinged a shield or cover, B, which may be shut entirely to exclude all air or opened more or less to admit a greater or less draft. This cover or shield may be made of various materials. I prefer, for the sake of lightness and economy, to construct it of stiff paper or straw-board, with the edges bound with metal, as shown.

At the ends of frame A are pivoted curved arms C, having their inner edges provided with a series of notches or indentations that engage pins *b*, projecting from the ends of cover B. By the tension of the small springs *c*, the notched arms are caused to bear upon the pins *b* with sufficient pressure to hold the cover or shield in whatever position it may be placed. The sides of the notches in arms C are inclined, so that they are lifted up to allow the pins to pass when a moderate degree of force is brought to bear on the cover through cords D E. At the lower ends of the arms C are projections *c*', which act as stops to limit the movement of the cover and prevent the pins *b* escaping from said arms. Two sets of cords, by means of which the cover may be opened or closed, are provided, one, D, for pulling down the shield or cover, attached near the upper edge thereof, the other, for pulling up or closing the cover, passing through the eyes *e e*' in the frame. Where the screen or ventilator is to be used under the lower sash, these cords are not needed, and may be dispensed with.

At the back of frame A is an extension-piece, F, also made of paper, pasteboard, straw-board, or similar material. This piece has attached to its face parallel strips *f*, of brass or other metal or material, which work in grooves or slits in the frame and permit the piece F to slide easily thereon. As the strips and their respective grooves are inclined in opposite directions, they serve also to keep the piece F from becoming detached. Spring friction devices *f*', (see Fig. 4,) secured to the back of the frame, act by their contact with

the metal bands around the piece F to hold it from accidental slipping when entirely closed, and to check its complete withdrawal. To remove the slide it is only necessary to apply sufficient force to cause the edge of the piece to depress the friction devices and ride over them.

In order to reduce the size of the device to the smallest compass, which for some purposes—
as, for instance, to carry it about the person for use in traveling in a railway-car—is desirable, the frame and screen are made smaller than usual, and the extension-piece F made in two parts hinged together, as shown in Fig. 3. The part F' can be folded back when desired to pack up the device for transportation, and it is also provided with runners or strips f, which take into the grooves in the back of the frame. This construction both reduces the size of the device and furnishes additional means for adjustment.

The shield or cover B not only regulates the supply of air, but also serves to deflect the same upward, preventing injurious draft. In this it is aided by the side pieces, B', of cloth, the edges of which are fastened to the frame and cover, respectively. Should any dust or other fine particles of matter sift through the screen a, they would strike against the shield B, and, falling down between it and the frame, be caught by the ledge G, which is or may be a strip of brass or other metal let into the frame A.

In use the ventilator would be placed in the window-frame, between the sash, which would be partly opened for that purpose, and either the upper or lower sill of the window-frame, the sliding extension-piece would be adjusted to uncover as much as deemed necessary of the perforate screen and to close up the space that the frame does not occupy, and the shield or cover set by means of the cords at the desired angle, in which position it will be retained by the notched arms, as explained. Small points a' in the frame penetrate slightly into the wood-work of the window and aid in holding the device securely in place.

The shield B and sliding piece F being made of very light material, and the whole device being readily reducible to small compass and to shape convenient for handling, the improved ventilator may be easily carried from place to

place, as its use may be needed, or may be carried in the pocket or satchel for use while traveling.

Having now fully described my said invention and the manner of carrying the same into effect, what I claim is—

1. In a window-ventilator, the combination of the frame, the shield hinged thereto, the spring-arms pivoted to said frame and provided with serrations or notches having inclined sides, and the pins fixed in said shield and engaging said spring-arms, substantially as described.

2. The combination of the frame inclosing a screen of wire or other material, the hinged shield or cover, and the notched arms bearing with yielding pressure on pins projecting from said shield or cover, substantially as and for the purpose described.

3. The combination, with the screen and hinged shield or cover, of the notched spring-arms engaging with pins on said cover, as explained, and having stops formed on their outer ends, substantially as and for the purpose described.

4. The combination of the frame, the screen, the hinged cover or shield, and the ledge or strip secured to said frame below said cover or shield, substantially as described.

5. The combination of the screen, the imperforate sliding extension-piece for regulating the size of the air-opening and adjusting said screen to different sizes of window, and the spring friction devices, substantially as described.

6. The combination, with the screen, of a two-part sliding extension-piece, substantially as described.

7. The combination, with the frame and open-work screen, of a sliding extension-piece provided with metal strips inclined in opposite directions working in slits or grooves in said frame, substantially as described.

In testimony whereof I have signed this specification in the presence of two subscribing witnesses.

EMMELINE W. PHILBROOK.
